UNITED STATES PATENT OFFICE.

ROBERT H. INGERSOLL, OF NEW YORK, N. Y.; CHARLES S. SMITH AND FREDERIC C. LEUBUSCHER, EXECUTORS OF SAID ROBERT H. INGERSOLL, DECEASED, ASSIGNEES TO ROBT. H. INGERSOLL, INC., OF NEW YORK, N. Y., A CORPORATION OF NEW YORK.

MECHANICAL PENCIL.

Application filed July 7, 1925. Serial No. 42,057.

The invention relates to new and useful improvements in mechanical pencils, and more particularly to the mechanism for advancing the lead and for locking the lead when positioned for writing.

An object of the invention is to provide a mechanical pencil of the above type with mechanism adapted to cooperate with the lead adjacent the forward or writing end thereof for intermittently propelling or advancing the lead, and for clamping the lead when the same has been projected to proper position for writing.

A further object of the invention is to provide a lead propelling mechanism for pencils wherein the means which advances the lead has a limited movement forward and backward toward the writing end of the pencil, and wherein devices are provided so that when said lead feeding means is moved forward, the lead will be moved forward therewith, and when said means is moved backward, the lead will be held from movement with said reciprocating feeding means.

A further object of the invention is to provide a lead feeding means of the above type wherein devices are provided for clamping the lead and said devices are caused by the lead feeding means to alternately grip and release the lead.

A still further object of the invention is to provide a pencil of the above type having a reciprocating sleeve through which the lead is passed and by which the lead is frictionally gripped with means for reciprocating the sleeve, and with clutching dogs operated by the reciprocating movements of the sleeve to engage and hold the lead from movement with the sleeve when said sleeve is retracted, and wherein said dogs are disengaged from the lead when the sleeve is moved in a forward direction.

A still further object of the invention is to provide a pencil of the above type wherein said sleeve is provided with means for gripping the lead when said sleeve is at one extreme end of its reciprocation.

A further object of the invention resides in the providing of an inner casing in which a plurality of leads may be stored, and means whereby said leads may be fed by gravity, one at a time, into the propelling means for feeding the lead to writing position.

These and other objects will in part be

obvious and will in part be hereinafter more fully disclosed.

In the drawings which show by way of illustration one embodiment of the invention—

Figure 1 is a longitudinal sectional view through the pencil embodying my improvements;

Fig. 2 is a longitudinal sectional view on an enlarged scale showing the clutch dogs as moved into engagement with the lead;

Fig. 3 is a similar view, but showing the clutch dogs as moved and held out of engagement with the lead;

Fig. 4 is a detail on an enlarged scale showing the forward end of the pencil and the split or slotted clamping sleeve therefor with the parts in position so that the lead is released from the sleeve, except for a slight frictional engagement between the sleeve and lead;

Fig. 5 is a similar view, but showing the parts shifted so that the sleeve clamps the lead, and

Fig. 6 is a detail showing the manner of mounting the dogs on the sleeve so that the sleeve may move bodily relative to the dogs supported thereby.

The invention is directed broadly to a mechanical pencil of the type wherein a lead is advanced by aid of mechanical structure and is clamped at the writing point when in position for writing. The pencil includes an outer casing which is formed, or provided, with the usual tapered nose portion at the writing end of the pencil. Located within this outer casing and telescoping therein, is an inner casing or barrel which extends slightly beyond the upper end of the outer casing so that a cap or finger piece may be attached thereto for moving said inner casing lengthwise of the outer casing. The lower end of this inner casing terminates at some distance back or up from the writing end of the pencil. The sleeve is connected to the lower end of said inner casing, and said sleeve is provided with a passage extending the entire length thereof.

The leads are placed in the inner casing where they are stored, and are directed, one at a time, into the passage through the sleeve. Located in the outer casing is a spring which bears against a fixed member in the casing, at one end, and at the other end, against a shoulder on the sleeve, and this spring normally moves the inner casing upwardly and away from the

writing end of the pencil. The operator, by pressing on the cap or finger piece at the upper end of the casing may move the inner casing downwardly, compressing the spring. This 5 sleeve is split or slotted from the lower end thereof upwardly for about two-thirds of its length, and the sides of the split portions are separated by the slots so as to form channels. The passage through the sleeve adjacent the 10 writing end of the pencil is of substantially the same size as the lead, so as to frictionally grip the same. The passage in the sleeve, however, throughout the greater portion of its length is larger, so as to permit the lead to 15 drop freely by gravity down into the sleeve as far as the frictional portion. The purpose of this frictional grip of the sleeve on the lead is to afford means whereby the lead may be moved forward when the sleeve is moved forward. The frictional grip is comparatively light and means is provided which consists of two opposed dogs which lightly engage the lead when the sleeve is retracted so as to hold the lead and prevent it moving back with the 25 sleeve, and thus it is the sleeve secures a new frictional grip upon the lead so that it may be fed forward and projected from the writing end of the pencil. Said sleeve and outer casing have cooperating means which cause 30 the split ends of the sleeve to grip the lead when the lead is in writing position, and the sleeve is at one end of its movement in the outer casing, so that the lead may be firmly held during writing.

35 Referring more in detail to the drawings, the improved mechanical pencil consists of an outer casing 1 within which is located an inner casing 1^a. The outer casing is provided with the usual tapered portion 2 at the writing end. The inner casing 1^a is considerably shorter than the outer casing, but is arranged therein so as to project beyond the upper end of the outer casing, so that a cap 9 may be attached thereto and form a finger piece 40 for moving the inner casing downwardly in the outer casing. This cap is also provided with a shoulder sleeve 10 which butts against the outer end of the outer casing and limits the downward movement of the inner casing. 45 Located at the lower end of the inner casing is a sleeve 3. This sleeve in the present embodiment of the invention projects beyond the end of the casing 1 and has a nose portion 4 formed with a cam face 5. The sleeve is split 50 or slotted for about three-fourths of its length, said slot extending from the lower end thereof up into the sleeve forming fingers, and the side edges of the split portions are spaced so as to form channels 14. The nose portion of the outer casing has a comparatively small opening 6 so that the sleeve back 55 from said cam portion 5 will slide freely therethrough. The end of the nose portion engages the cam portion 5 when the sleeve is 60 moved to the right, as shown in Fig. 5. The end of the casing sliding up on the cam 5 will cause the split end portion of the sleeve to grip the lead at a point very close to the writing point and thus clamp the lead for writing. 65 The sleeve 3 is rigidly attached at its upper end to the inner casing or barrel 1^a. This is accomplished by providing the sleeve with a collar 3^a. Said collar 3^a snugly fits within the lower end of the inner casing 1^a and may be secured thereto in any suitable way. The 70 sleeve is provided with a passageway 7^a which extends throughout the entire length of the sleeve. This passageway 7^a at the lower end, has a portion thereof indicated at 13 in Fig. 4, which is of smaller diameter than the remainder of the passageway through the sleeve indicated at 13^a in Fig. 4. The lead 7 extends down into the passageway 7^a in the sleeve 3 and is fed through the sleeve to writing position in the manner hereinafter 75 to be described. The portion 13 of the passageway is of substantially the same diameter as the diameter of the lead, and will frictionally grip said lead. This frictional grip is sufficient so as to move the lead with the 80 sleeve, provided the lead is not restrained against movement with the sleeve. The upper portion of the passageway, however, indicated at 13^a, is larger than the lead, and the collar 3^a has a cone-shaped portion 23 leading 85 to this passageway, so that the leads stored in the chamber 24 formed by the inner casing may pass by gravity into the passageway 7^a. It is understood, of course, that while the 90 pencil is shown in the drawings as horizontal, this of course, does not illustrate the proper position of the pencil during writing, or during handling. When the pencil is in writing position, it is nearly upright, and the leads, of course, will pass by gravity to the lower 95 end of the chamber 24 and rest in the cone-shaped recess 23. As one lead is used up, another passes automatically into the sleeve and takes its place, and thus it is that the leads are automatically replenished. Located 100 within the outer casing 1 and below the inner casing 1^a, as a partition or retaining collar 11 which is rigidly secured to the outer casing 1 in any suitable way. Between this retaining collar 11 and the collar 3^a attached 105 to the inner casing 1^a, is a spring 12. This spring bears at its lower end on the collar 11 and at its upper end against the collar 3^a. The spring normally tends to move the inner 110 casing 1^a upwardly and away from the writing end of the pencil. The operator, through the cap or finger piece 9 can move the inner casing downwardly by compressing the spring. The downward movement of the inner casing 1^a and the sleeve 3 which is rigidly 115 attached thereto, will move the lead downwardly and cause it to project and remain beyond the end of the outer casing 1^a. This is brought about through the frictional grip 120 of the portion 13 of the sleeve 3 on the lead 130

and cooperating retaining dogs 15 and 16, which dogs and their mode of operation will now be described.

These dogs 15 and 16 are located in the channels 14 formed by the splitting of the sleeve 3. These dogs are pivotally mounted on a spring wire 17 which is located outside of the sleeve 3 and encircles the same. This spring wire has a frictional grip upon the sleeve, but the sleeve can move within this spring pivot ring whenever the dogs are held from movement with the sleeve. The fixed collar 11 has the lower end thereof formed cone-shaped as indicated at 21 in Fig. 2 of the drawings. Secured to this fixed collar 11 is a sleeve 11^a. The inner diameter of this sleeve is larger than the outer face of the cone portion 21 of the sleeve 11^a. The lower end of the sleeve 11^a has an inwardly extending lip 19. Between this lip, which is spaced some distance from the cone-shaped portion 21, there is a recess formed by the sleeve 11^a which houses the upper ends of the dogs 15 and 16. The dogs 15 and 16 are provided with tapered ends 22 which are adapted to cooperate with the cam faces of the cone portion 21 of the collar 11. These dogs are also provided with shoulders 20 which are adapted to cooperate with the lip 19. The spring 17 acts as a pivotal support for the dogs and holds the dogs on the sleeve 3^a. The lower ends of the dogs which are indicated at 15^a and 16^a, respectively, are adapted to be moved into light engagement with the lead 7 as indicated in Fig. 2, or moved and held out of engagement with the lead as indicated in Fig. 3. The cone-shaped cam 21 cooperating with the tapered ends 22, swing the dogs on the pivot spring into contact with the lead, while the lip 19 on the sleeve 11^a cooperating with the shoulder 20 on the dogs, will move them out of engagement with the lead and hold the dogs out of engagement with the lead. The purpose of these dogs is to restrain the lead from movement when the sleeve is retracted for the purpose of the frictional portion of the same obtaining a new grip on the lead.

When the finger piece or cap 9 is released, the spring 12 moves the inner casing to the right as viewed in Fig. 1, that is, away from the writing end of the pencil. The sleeve 3 being rigidly attached to said casing will move therewith. When the sleeve moves to the right as viewed in these figures, the dogs 15 and 16 will move therewith, by reason of the fact that the pivot spring engages the sleeve 3 with sufficient frictional grip as to move the dogs therewith. This movement to the right will cause the tapered ends 22 of the dogs to engage the cone-shaped portion 21 of the sleeve 11, which tilts the dogs so that they will lightly grip the lead. This occurs on the very first part of the upward movement of the sleeve 3. The dogs will be

brought into engagement with the cone-shaped portion 21 which will restrain any further movement thereof, and the dogs engaging the lead will hold the lead so as to overcome the frictional grip of the portion 13^a of the sleeve thereon. Therefore, the sleeve will move upwardly along the lead.

The dogs 15 and 16 lie in the channels 14 in the sleeve, and as these channels extend from a point well above the dogs to the lower end of the sleeve, the sleeve can move freely, although the dogs are restrained from movement.

After the sleeve is moved upwardly to the limit of its movement, then the sleeve has a new frictional grip upon the lead, and

when the sleeve is moved downwardly, it will carry the dogs downwardly into engagement with the lip 19 which rocks the dogs out of engagement with the lead, and permits the lead to move freely with the sleeve.

The dogs have a very limited movement with the sleeve which is solely for the purpose of moving the dogs into and out of engagement with the lead.

While in engagement with the lead, they do not move endwise of the outer casing, and therefore, would hold the lead from movement with the sleeve.

When the dogs are moved out of engagement or into neutral position, they still have no endwise movement with the outer sleeve.

The only function of the dogs is to prevent the lead from returning with the sleeve when the sleeve is retracted or repelled.

The dogs have nothing whatever to do with the feeding of the lead forward, excepting that they hold the lead when the sleeve is retracted for the purpose of overcoming the friction which the sleeve has on the lead.

At no time do the dogs grip into the lead so as to indent it and cause it to break when exposed for writing.

It is noted that this portion 13 of the sleeve has merely a frictional grip on the lead, when in its downward movement, and not a real holding or clamping grip thereon.

In order to clamp the lead when in writing position, the ball shaped cams 4 on the sleeve and the cam faces 5 and 6 on the outer casing are brought into contact by the action of the spring, which forces the split end of the sleeve into tight gripping engagement with the lead.

In the present embodiment of the invention, of course, this is accomplished through the action of the spring 12 forcing the inner casing 1^a and the sleeve 3 connected thereto upwardly when the cap or finger piece 9 is released.

In other words, the operator by intermittently pressing on the finger piece will feed the lead step by step out of the writing end of the pencil, but when the finger piece or cap is released, then the spring

moves it to its initial upward position where the lead is clamped by the split end of the sleeve through the action of the cams just referred to.

From the above description it will be noted

that I have provided a mechanical pencil wherein devices operate upon the lead adjacent the writing point, both for feeding the lead forward and for gripping the lead and holding it when in writing position. Therefore, the leads can be used right up to the last small end portions thereof, and furthermore, the lead is held in proper condition for writing without any chance of wobbling, and 10 without any chance of being forced back up into the pencil by the pressure of writing, and furthermore, there is little or no chance of the lead jamming.

As has already been noted, when the pencil is placed in a vertical position with the writing end down, or in any position so that the writing end is the lowest, the leads will pass by gravity from the chamber 24, one at 15 a time, into the passageway 7^a, and the sleeve 20 3 with the cooperating dogs will take up an intermittent feed of the initial feed and those to follow. It has also been noted that the drawings are not intended to show the pencil in position so that the lead is fed by gravity into this passageway 7^a. The purpose of the drawings is to show the structure and not the mode of operation of the pencil. It will 25 be readily understood by those skilled in the art, however, how the leads are fed one after another by gravity, into the sleeve which takes up an automatic intermittent feed of the leads, and which also clamps the lead at the writing point when it is in writing 30 position.

While I have shown my inner casing as moved by the cap or finger piece pressed in opposition to a spring, it will be understood, of course, that other ways may be obvious for moving this inner casing back and forth. In 35 fact, it may be moved positively in both directions by the operator, and the sleeve and the cooperating holding dogs will function in precisely the same manner. It will be understood, therefore, that the invention is not limited necessarily to what might be called a 40 punch type of pencil, but is broad enough to cover other means for operating the sleeve 3, and therefore, changes in the details of construction and arrangement of the parts may 45 be made without departing from the spirit of the invention as set forth in the appended 50 claims.

Having thus described the invention, what I claim as new and desire to secure by Letters-Patent, is—

1. A mechanical pencil comprising a casing, and reciprocating member associated therewith for supporting and propelling the lead and devices carried by said member for clamping said lead adjacent the writing point thereof when said propelling means is at one extreme end of its movement.

2. A mechanical pencil comprising a casing, and reciprocating means associated therewith for supporting and propelling the

lead and for clamping said lead adjacent the writing point thereof when said propelling means is at one extreme end of its movement, and for releasing said clamp and means for restraining said lead from movement while 70 said propelling means is retracted for the purpose of engaging the lead to further advance the same, said restraining means being independent of said clamping means.

3. A mechanical pencil comprising a casing, a sleeve located within said casing and projecting from the casing at the writing end of the pencil, means connected to the casing for moving the sleeve back and forth in the casing, said sleeve having a passage therethrough for the lead and having a split end adapted to grip the lead and hold it in writing position, the passage through the sleeve adjacent the end thereof and for a portion of its length being so proportioned relative to 80 the lead as to make a light frictional grip upon the lead, said passage above the frictional gripping portion being larger in diameter than the lead, and means associated with the sleeve for preventing the retraction of the lead with the sleeve when the sleeve is retracted whereby a new frictional grip upon the lead is obtained for advancing the lead.

4. A mechanical pencil comprising an outer casing, an inner casing located in said outer casing and having a compartment in which the leads may be stored, a sleeve located within said outer casing and rigidly connected to said inner casing, said sleeve having a passage therethrough for the lead, and a split end adapted to be forced into contact with the lead for holding it in writing position, said passage through the sleeve adjacent the end thereof and for a portion of its length being so proportioned relative to 100 the lead as to make a light frictional grip upon the lead at all times, means associated with the sleeve for preventing the retraction of the lead with the sleeve when the sleeve is retracted whereby a new frictional grip upon the lead may be had for advancing the same, said passage at the upper end of said sleeve 105 terminating in a cone-shaped recess opening into the compartment within the inner casing so that leads stored in the inner casing may 110 pass by gravity into the passage through the sleeve and be intermittently fed forward to writing position.

5. A mechanical pencil comprising an outer casing, an inner casing within said outer casing, means whereby said inner casing may be moved back and forth in said outer casing, a sleeve rigidly connected to the lower end of said inner casing, said sleeve having a passage therethrough for the lead, and a split end, means whereby said outer casing forces the split end of said sleeve into engagement with the lead for holding it in writing position when the inner casing is at one end of its movement, a passage through 120 125 130

- said sleeve having a portion thereof at the split end so proportioned relative to the lead as to frictionally grip the lead, the portions of the sleeve formed by the splitting thereof being spaced from each other so as to provide channels, holding dogs located in said channels, means for pivotally supporting said dogs, said pivotal support for the dogs extending about the sleeve and having a slight frictional engagement therewith, whereby when unrestrained, the dogs will move with said sleeve, devices cooperating with said dogs for moving the same into engagement with the lead when the sleeve is moved away from the writing end of the pencil for restraining the lead against movement with the sleeve whereby said sleeve may be moved upwardly on the lead for a new frictional grip thereon, and devices cooperating with the dogs for moving the same out of engagement with the lead when the sleeve is moved in the opposite direction whereby the frictional grip of the sleeve on the lead will advance the lead and cause the same to project beyond the end of the outer casing and the sleeve.
6. A mechanical pencil comprising a casing, a sleeve located within said casing and projecting from the casing at the writing end of the pencil, means connected to said sleeve for moving said sleeve back and forth in the casing, said sleeve having a passage therethrough for the lead and having a split end making fingers adapted to grip the lead and lock it in writing position, said passage through the sleeve being so formed that said sleeve has a light frictional grip upon the lead at all times, and means associated with said sleeve for preventing the retraction of the lead with the sleeve when said sleeve is retracted to obtain a new frictional grip upon the lead for advancing the same, said split end of the sleeve and said casing at the writing end thereof having cooperating means adapted to cause the split end of the sleeve to grip the lead when the sleeve is retracted.
7. A mechanical pencil comprising an outer casing, an inner casing located within said outer casing, a sleeve located in the outer casing and connected to said inner casing, a spring in the outer casing for moving the inner casing and sleeve away from the writing end of the pencil, a cap or finger piece attached to the inner casing for moving the sleeve and inner casing toward the writing end of the pencil, said sleeve having a passage therethrough for the lead, channels in said sleeve leading into said passage, said passage having a portion thereof of such diameter as to frictionally grip the lead and move the lead with the sleeve, unless restrained from movement, dogs located in said channels, means for pivotally supporting said dogs, and devices for moving said dogs into contact with the lead when the inner casing is moved upwardly away from the writing end of the
- pencil so as to restrain the lead from movement whereby said sleeve moves along the lead and obtains a new frictional grip thereon.
8. A mechanical pencil comprising an outer casing, an inner casing located within said outer casing, a sleeve located in the outer casing and connected to said inner casing, a spring in the outer casing for moving the inner casing and sleeve away from the writing end of the pencil, a cap or finger piece attached to the inner casing for moving the sleeve and inner casing toward the writing end of the pencil, said sleeve having a passage therethrough for the lead, channels in said sleeve leading into said passage, said passage having a portion thereof of such diameter as to frictionally grip the lead and move the lead with the sleeve, unless restrained from movement, dogs located in said channels, means for pivotally supporting the dogs, devices for moving said dogs into contact with the lead when the inner casing is moved upwardly away from the writing end of the pencil so as to restrain the lead from movement whereby said sleeve moves along the lead and obtains a new frictional grip thereon, and devices cooperating with said dogs for moving the dogs out of engagement with the lead when the sleeve and inner casing are moved toward the writing end of the pencil so that said lead is unrestrained by the dogs and free to move with the sleeve.
9. A mechanical pencil comprising an outer casing, an inner casing located within said outer casing, a sleeve located in the outer casing and connected to said inner casing, a spring in the outer casing for moving the inner casing and sleeve away from the writing end of the pencil, a cap or finger piece attached to the inner casing for moving the sleeve and inner casing toward the writing end of the pencil, said sleeve having a passage therethrough for the lead, channels in said sleeve leading into said passage, said passage having a portion thereof of such diameter as to frictionally grip the lead and move the lead with the sleeve, unless restrained from movement, dogs located in said channels, means for pivotally supporting said dogs, devices for moving said dogs into contact with the lead when the inner casing is moved upwardly away from the writing end of the pencil so as to restrain the lead from movement whereby said sleeve moves along the lead and obtains a new frictional grip thereon, and devices cooperating with said dogs for moving the dogs out of engagement with the lead when the sleeve and inner casing are moved toward the writing end of the pencil so that said lead is unrestrained by the dogs and free to move with the sleeve, said sleeve having the end thereof split whereby said sleeve may be moved into clamping engagement with the lead, and means whereby the

outer casing will move said split end of the sleeve into gripping contact with the lead for holding the lead in writing position when the sleeve and inner casing are at one end of 5 their movement.

10. A mechanical pencil comprising a casing, a sleeve located within said casing, at the writing end thereof, means for moving said sleeve lengthwise of said casing, said sleeve 10 having a passage therethrough for the lead and a split end, said passage being so proportioned relative to the lead as to make light frictional engagement therewith so that said lead will move with the sleeve unless restrained against movement, devices operated 15 by the movements of the sleeve for engaging the lead and restraining the same against movement when said sleeve is moved away from the writing end of the pencil.
20. 11. A mechanical pencil comprising an outer casing, an inner casing, a sleeve located within said outer casing and connected to said inner casing, said inner casing forming a compartment for storing the writing 25 leads, said sleeve having a passage formed therethrough for the leads, and a cone-shaped recess at the upper end of the sleeve leading into said compartment for directing the leads into the passage through the sleeve,
30. said sleeve having means for frictionally engaging the lead so as to cause the same when in the passage to move with the sleeve, means for moving said sleeve and inner casing lengthwise of the outer casing, and means 35 associated with the sleeve for restraining the movements of the lead in the sleeve when the sleeve is moved away from the writing end of the pencil whereby said sleeve may ob-

tain a new frictional grip upon the lead for advancing the same.

12. A mechanical pencil comprising an outer casing, an inner casing, a sleeve located within said outer casing and connected to said inner casing, said inner casing forming a compartment for storing the writing leads, 45 said sleeve having a passage formed therethrough for the leads, a cone-shaped recess at the upper end of the sleeve leading into said compartment for directing the leads into the passage through the sleeve, said sleeve having means for frictionally engaging the lead so as to cause the same when in the passage to move with the sleeve, means for moving said sleeve and inner casing lengthwise of the outer casing, means associated with the 55 sleeve for restraining the movement of the lead in the sleeve when the sleeve is moved away from the writing end of the pencil whereby said sleeve may obtain a new frictional grip upon the lead for advancing the 60 same, and means associated with the sleeve for clamping the lead when the lead is in proper position for writing.

13. A mechanical pencil comprising an outer casing, means located within the outer 65 casing and adjacent the writing end thereof and movable endwise of the casing for intermittently feeding the lead forward to writing position, means for restraining the lead from movement when said first named 70 means is retracted, and means at the writing end of the pencil independent of the restraining means for clamping the lead and holding the same firmly during writing.

In testimony whereof, I affix my signature,
ROBERT H. INGERSOLI.
